UNITED STATES PATENT OFFICE

2,674,761

CONCEALED HINGE

Harold Arthur Weiss, Oak Park, Mich., assignor
to Soss Manufacturing Company, Detroit,
Mich., a corporation of Maine

Application August 3, 1951, Serial No. 240,148

5 Claims. (Cl. 16—164)

1

This invention relates to concealed hinges for use on cabinets, particularly refrigerator cabinets and home freezers. It is the object of the invention to provide a multiple leaf hinge of the general type of a "Soss" hinge, which can be used on a refrigerator for supporting a door so that the door will be stopped in its opening movement at approximately 90°. This will be very advantageous in many kitchens, especially where the refrigerator is placed in an alcove and it is desirable to stop the door when it has swung to a perpendicular position, and the door will not swing beyond the side of the cabinet because the hinge pulls the hinging edge of the door in toward the opening in the cabinet as the door is swung open.

Another object of the invention is to provide a hinge which will, when the door is closed, lock the hinge edge of the door to the cabinet by means of a toggle thrown over center. Still another object of the invention is for the door to open by the weatherstrip separating from the jamb of the door and not being drawn across the jamb face to scuff the weatherstrip and the face of the jamb.

An advantage to the refrigerator manufacturer is that the hinge mounts flat on the surface and does not cut into the door or cabinet wall.

Referring to the drawings:

Fig. 1 is a small elevational view of a refrigerator equipped with my concealed hinge.

Fig. 2 is a section on the line 2—2 of Fig. 1, showing the door closed.

Fig. 3 is a section on the line 3—3 of Fig. 2.

Fig. 4 is a similar section showing the door partially open.

Fig. 5 is a section on the line 5—5 of Fig. 4.

Fig. 6 is a section through the refrigerator and the door showing the door completely open and stopped in the 90° position.

Fig. 7 is a fragmentary section through the cabinet and lid showing a modified form of the hinge.

Fig. 8 is a similar view of the modified form of the hinge with the lid open.

Fig. 9 is an elevational view of the hinge taken from the right of Fig. 8.

The cabinet here shown is a refrigerator and has the usual insulated wall 1. A mounting plate 2 is secured thereto by the bolts and nuts 3. A mounting plate 4 is secured to the inside of the door by the bolts and nuts 5. The mounting plate 2 has the shelf 6 which pivotally supports at 7 the hockey type or hooked lever of the first order 8 which has its end pivoted at 9 to lugs

2

of the mounting plate 4 on the door. The turned out end of the lever 8 is pivoted at 11 to the short links 12 and 12a which in turn are pivoted to the inner ends 13a of the second levers of the first order 13. The outer ends of levers 13 are pivoted at 14 to the control arm 15. These levers have been spoken of as though they were single leaf arms, but if Figs. 3 and 5 are examined it will be seen that the arm 8 is formed of a pile of eight plates. There are two arms 13, each of which is made up of two plates. There are two links 12 and 12a, each of which is made up of two plates. There is an upper shelf 6 and a lower shelf 16a on the mounting plate 2. The power end 8a of the first mentioned lever 8 is secured to the links 12 and 12a by means of the long pin 11 (see Fig. 3). The upper and lower shelves 6 and 16a of the mounting plate 2 are provided with the down turned boss 17 and the up turned boss 18 respectively. The two levers 13 are pivoted to the upper and lower bosses by means of the long pin 20, and are separated and kept properly spaced by the spacing sleeve 19. The power arms 13a of the levers 13 are part of a pair of toggle arms 21 connected together by the two pins 21 and 21a at the knee of the toggle.

22 designates the jamb face of the refrigerator cabinet. 23 is a thick pad or rubber weatherstrip adapted to bear against the jamb face of the refrigerator. 24 designates the recess in the refrigerator pillar in which the mounting plate and part of the concealed hinge are located.

Fig. 2 shows the refrigerator door closed. The controlling arm 15 is made up of four plates (see Fig. 5) and is pivoted to the two brackets 25 and 25a of mounting plate 4 by pin 26.

When the door is opened by pulling on the handle 27, the door swings open as shown in Fig. 4 and then keeps on swinging until, as in Fig. 6, the lever 8 has the power arm 8a striking the stop 28 on the mounting plate 2 of the cabinet. This holds the door in a substantially perpendicular position and prevents it from swinging beyond the proper position and possibly striking the wall or something else in the way. The concealed hinge has the very useful function of pulling the hinging edge of the door toward the opening in the cabinet so that the door does not swing out beyond the side of the cabinet. This is very useful when the cabinet is located in an alcove or where the hinge is used upon a domestic freezer with a lid which swings to near vertical or vertical position.

When the door or lid closes, the toggle formed by the link 12 and the short arm 13a of the

lever 13 swings from a position at one side of the straight line between the two pivot points 20 and 11 to a position on the other side of the straight line between these two pivots. In Fig. 2 the toggle arms 12 and 13a are outside the center line between their pivots 11 and 20. As the door opens, the toggle arms pass center and take the angular position shown in Fig. 4 and the acutely angular position shown in Fig. 6. If a force is exerted on the hinge edge of the door tending to lift or pry the hinge edge open, this operates directly on the lever 8 which swings on its fulcrum and then thrusts clockwise on the pivot 11 (Fig. 2), and this simply pushes downward on the toggle set and locks the door all the tighter to the cabinet at the hinge edge. On the other hand, if an effort is put on the door tending to rotate the door outwardly from the free edge on the pin 9, this causes the control arm 15 to pull on the lever 13 and break the toggle lock and swing the toggle arms inwardly as shown in Figs. 4 and 6.

In the modified form of the invention shown in Figs. 7 and 9, the levers 8b and 13b are not hockey stick shaped levers, but 13b is nearly a straight arm and 8b is a T arm. The arm 13b is a lever of the first order. There are two of these levers 13b, each with two plates. The main hinge arm or lever 8b, which is made up of a plurality of leaves or plies is T shaped with a slight hook or hockey stick form on the end of the lever which is pivoted to the door mounting plate at 20b. One end of the bar of the T or hooked lever 8b is pivoted at 21b to the connecting links 12b. There are two of these links, each of only one ply. Strong tensile springs 30 are secured one to each end of the pivot pin 21b. The other end of the bar of the T lever 8b is fulcrumed to the cabinet mounting bracket 2b by means of the pivot pin 7b. This type of hinge is intended primarily for a cabinet such as a domestic freezer, which has an upwardly swinging lid.

In the fully closed position, Fig. 7, the spring pulling on pivot pin 21b exerts a pull on the line inwardly of a straight line between pivots 14b and 20b, and also a straight line position between pivots 14b and 21b. It is believed that the effective toggle in the fully closed position is between the pivots 14b and 20b and includes as toggle members the spring 30 and the power arm of lever 8b. As soon as one starts to lift the lid for the first inch or two there is spring resistance to the lifting, but as soon as the lid has been raised a couple of inches the knee of this toggle 21b passes the straight line between pivots 20b, and 14b, the two main hinge arms or levers 8b and 13b nearly completely fold up in near parallel relationship as shown in Fig. 8 and the control arm 15b pulls almost all the way down, thereby shortening the spring very considerably from the length shown in Fig. 7 where the lid is closed. In all this shortening action, this tractile spring has been pulling to help lift the lid and acting as a counterpoise spring to hold the lid partially open or fully open. Of course as a counterpoise spring to effect this holding action, the spring has to be of the correct strength. If it is too strong, it will pull the lid completely open. If

it is too weak, it will fail to hold the lid in a position of partial opening.

In the hinge of Figs. 7 and 9, the checking lug 31 is on the lever 13b and this lug strikes the lever 8b (Fig. 8) to check the door in the fully open position of 98°.

The feature of these two hinges is that this hardware is completely hidden when the door is closed. Either type of hinge checks the door or lid at approximately 90°. Either type of hinge pulls the hinging edge of the door or lid in toward the cabinet opening so as not to hit an adjoining wall or other things. When the hinge is used for a lid, the load of the fully open lid is on the two levers and control link in almost straight lines of their length, so as to put the least strain on the levers and link.

In order to refer to both doors and lids in the claims, I have used the all inclusive word "closure."

What I claim is:

1. A concealed hinge and closure check having in combination a mounting plate for attachment to a stationary pillar, a mounting plate for securing to a closure, a hooked end lever of the first order pivoted to the mounting plate of the closure at one end of the lever and fulcrumed at the elbow of the hook on the mounting plate of the stationary pillar, a second lever of the first order fulcrumed on the mounting plate of the stationary pillar, a short link connecting the adjacent ends of the two levers, and a control link connecting the mounting plate for the closure with free end of the second named lever.

2. The combination claimed in claim 1 in which there is a stop provided for arresting the levers when a substantially perpendicular opening of the door has been had.

3. The combination claimed in claim 1 in which the levers and short link form a toggle which throws over center to lock the lid edge in the final closing movement.

4. The combination claimed in claim 1 in which a tractile counterpoise spring connects the joint at the swinging end of the control link and the adjacent lever and the joint between the short link and the hooked end of the other lever.

5. The combination claimed in claim 1 in which the first mentioned lever comprises a pile of eight plates, the second mentioned arm comprises four plates in two piles, separated by a spacing sleeve, and the short connecting linkage comprises two links, each on the outside of the two levers but at opposite sides, and in which the control arm comprises a pile of four plates between the two second mentioned levers.
